UNITED STATES PATENT OFFICE.

WILLIAM J. SATTERLEE, OF DANBURY, CONNECTICUT.

SUPPORT OR EASEL FOR PICTURE-CARDS AND THE LIKE.

1,237,560.

Specification of Letters Patent. Patented Aug. 21, 1917.

Application filed December 16, 1916. Serial No. 137,451.

To all whom it may concern:

Be it known that I, WILLIAM J. SATTERLEE, a citizen of the United States, residing at Danbury, county of Fairfield, State of Connecticut, have invented an Improvement in Supports or Easels for Picture-Cards and the like, of which the following is a specification.

This invention relates generally to supports in the nature of easels for the display of mounted photographs, picture-cards and post-cards, advertising display-cards, and the like, and has for its object the provision of an exceedingly inexpensive device of this character, yet one which will be amply strong and stable in use.

My invention consists, generally, in a frame, brace and picture or card engaging and retaining means all formed from a single strand of wire, and further consists in various details of construction, configuration and arrangement of parts as hereinafter described and particularly pointed out in the claim.

My invention will be more readily understood by reference to the accompanying drawings, forming a part of this specification, in which—

Figure 1 is a perspective view of a support or easel embodying my invention, showing the manner in which the card or picture is mounted therein, a part of the latter being broken away, and

Fig. 2 is a similar view of a slightly modified form of the device.

Referring now to the drawings in detail, it will be noted that my improved support or easel is constructed in its entirety from a single strand of wire. In the preferred construction, as shown in Fig. 1, the strand of wire is bent into substantially rectangular form, providing the side portions 5 and 6, the bottom portion 7, the top portion comprising the two parts 8 and 9 of the strand which are suitably joined together at the middle of said top portion, preferably by twisting the meeting parts of the strand, as at 10, thus leaving projecting ends 11 and 12 of the strand which may be bent downwardly at a proper supporting angle with the plane of the frame and with each other, and made of such length, that a stable prop is provided to support the frame upon any flat surface in a slightly tilted position.

In forming the frame, what may be termed double loops, or pairs of loops are provided at the corners thereof. At each end of the bottom portion 7 of the frame the wire is formed into a relatively small loop 13 and again into a contiguous and corresponding loop 14 prior to being directed upwardly to form the side portion 5, at the top end of which a pair of corresponding loops 15 are formed from which the wire is carried laterally to provide the top portion 6 of the frame, as described. It is to be noted in connection with the pair of loops at each corner of the frame that the cross or connecting portion 16 between the loops passes over or in front of the side and top or bottom portions of the frame, whereby what may be termed a spring clip is formed at each corner thereof, so that a photograph, card, or the like, 17, of proper size, may be mounted in said frame by merely passing the corners of the former underneath or back of the connecting portion 16 of the loops and the same firmly but removably held in said frame by the inherent resiliency of the metal of which the wire is formed.

It will be apparent that the relative dimensions of a frame and brace embodying my invention are not important, nor is it essential that the frame be of general rectilinear character. In fact, when employed to display a relatively very thin and flexible card, or one which has been treated in such manner as to produce a tendency to curl or become distorted, it is oft-times highly desirable to provide some form of backing therefor, and this I may provide by in-curving the side and bottom, and possibly the top, portions of the wire of the frame, as shown in Fig. 2. In this construction, it will be seen that the deflection of these portions of the wire toward the center provide back supports for the picture or card which are located intermediate the center and the extreme edges of the former, thereby not only better resisting inherent forces tending to distort or curl the contained sheet, but also better guarding against accidental dislodgment thereof.

Many other modifications of the construction, contour and arrangement of parts of a device embodying my invention will doubtless readily suggest themselves to those skilled in the art to which it appertains, and

I therefore do not limit my invention to the specific details of a device embodying the same as herein shown and described.

I claim as new and desire to secure by Letters Patent:

A supporting device of the character described comprising a single strand of wire presenting a rectangular body having diagonally disposed pockets at its corners, said pockets having retaining portions in front of the plane of said body, portions of said

wire being twisted together to preserve the shape of the body, the twisted portions extending diametrically inward and terminating in two divergent supporting legs of 15 equal length, said body being adapted to support the back of a picture or the like and invisible from the front when said picture is in position.

In testimony whereof I affix my signature. 20

WILLIAM J. SATTERLEE.
